UNITED STATES PATENT OFFICE.

MAX NYDEGGER, OF ELIZABETH, NEW JERSEY.

KNITTING-MACHINE.

1,072,639.

Specification of Letters Patent.

Patented Sept. 9, 1913.

Application filed May 2, 1912. Serial No. 694,630.

To all whom it may concern:

Be it known that I, MAX NYDEGGER, a citizen of Switzerland, and resident of the city of Elizabeth, county of Union, and State of New Jersey, have invented an Improvement 5 in Knitting-Machines, of which the following description, in connection with the accompanying drawings, is a specification, like letters on the drawings representing like 10 parts.

The present invention relates to an improvement in knitting machines of the straight bed type, and particularly to that 15 class of machines commonly used in knitting sweaters or garments of similar texture.

The object of the invention is to provide a machine with which it is possible to knit the body and pockets of a sweater or knit- 20 ted garment in a continuous operation.

It has heretofore been the custom, in making garments of the kind referred to, to knit the body and pocket portions separately and afterward to sew or splice the 25 pocket into the fabric of the body of the garment. By the use of my improvement, the pocket may be knitted in at its proper place in the course of knitting the whole garment without removing the fabric from 30 the machine and without interrupting the continuity of the knitting. It will be obvious that such improvement will serve to reduce materially the amount of hand labor on knitted sweaters and the like and obviate 35 the necessity for having an extra machine to make the pocket portions.

Inasmuch as the improvements consist of a modification in the structure and arrangement of needles and simple additional mech- 40 anism in the cam box, they may be incorporated in existing machines of the straight bed type at very little inconvenience and expense.

One practical embodiment of my invention 45 is shown in the accompanying drawings, in which,

Figure 1 is a front elevation of the needle plate with complement of needles, Fig. 2 is a detail plan view of a cam box, and Figs. 50 3 and 4 are longitudinal and cross sections on the lines 3-3 and 4-4 respectively of Fig. 2.

The gist of the present invention lies in providing mechanism whereby a certain set 55 or sets of needles in the same needle plate

may be actuated while the other needle remains inoperative. For this purpose I prefer to equip a portion of the needle plate 1 with needles 2 having high butts 5 while the remaining needles 3 are the ordinary or 60 low butt needles.

In normal operation the cam box 4 reciprocates back and forth across the needle plate 1, engaging, by means of cams 6 and 7, the butts of all the needles. These cams 65 and the well known mechanism which causes them alternately to engage and pass over the needle butts are mounted on a cam plate or lock plate 8 which is itself adapted to be raised and lowered. Attached to the cam 70 plate, are plungers 9 and 10 provided with slots 11 and 12 respectively, having both horizontal and inclined bearing surfaces. A slidable bar 13, suitably mounted in the cam box, engages these slots 11 and 12 in 75 the plungers. As shown in Fig. 3, the cam plate is in normal or low position with the cam box moving in the direction of the arrow. In order to shift the cam plate and cams to a higher position, the bar 13 is 80 pulled in the direction of the arrow by means of a handle 14, thus causing the inclined faces 15 of the bar 13 to bear upwardly against the undercut faces 16 in the plungers and consequently to raise the plungers so that a horizontal part of the bar will 85 bear against the horizontal surfaces of the slots in the plungers and hold the latter securely in their resulting raised position, wherein only the high butt needles will be 90 engaged by the cams in their course across the needle plate. In a similar manner, a third position of the cam plate may be effected by providing another incline and raised portion in the bar. In this highest 95 position, the cam box may be made to traverse the needle plate without operating any of the needles.

I claim as my invention:—

1. In a knitting machine, the combination with a cam box having a cam plate movable relatively thereto, of plunger rods attached to the said cam plate, and a bar in slidable engagement with the said plunger rods to effect the raising and lowering of 105 the cam plate.

2. In a knitting machine, the combination with a cam box having a cam plate movable relatively thereto, of plunger rods attached to the said cam plate and having slots in 110

the sides, and a bar having inclined faces adapted to slide in the said slots.

3. In a straight knitting machine, the combination with a cam box, of a cam plate adapted to be moved vertically in the cam box, and means to effect the said vertical movement and secure the cam plate in operative position.

4. In a knitting machine, the combination with a cam box, of a cam plate adapted to be moved vertically in the cam box, plungers mounted upon the cam plate, and a bar adapted to engage the said plungers and to secure them in operative position.

15 5. In a knitting machine, the combination with a cam box, of a cam plate adapted to be moved vertically in the cam box, plungers mounted upon the lock plate and hav-

ing slots in their sides, and a bar having alternating horizontal and inclined portions 20 adapted to slide in the said slots.

6. In a knitting machine, the combination with a cam box, of a cam plate carried by plungers having slots in their sides, each of the said slots being formed to provide upwardly exposed inclined and horizontal bearing surfaces and downwardly exposed horizontal and inclined bearing surfaces, and a bar adapted to engage the said slots.

In testimony whereof, I have signed my 30 name to this specification, in the presence of two subscribing witnesses.

MAX NYDEGGER.
